UNITED STATES PATENT OFFICE.

STACY B. HASELTINE, OF CHICAGO, ILLINOIS, ASSIGNOR TO WILLIAM H. MINER, OF CHAZY, NEW YORK.

YOKE FOR DRAFT-RIGGINGS.

1,355,968.

Specification of Letters Patent.

Patented Oct. 19, 1920.

Application filed April 3, 1919. Serial No. 287,254.

To all whom it may concern:

Be it known that I, STACY B. HASELTINE, a citizen of the United States, residing at Chicago, in the county of Cook and State 5 of Illinois, have invented a certain new and useful Improvement in Yokes for Draft-Riggings, of which the following is a full, clear, concise, and exact description, reference being had to the accompanying drawings, forming a part of this specification.

This invention relates to improvements in yokes for draft riggings.

It is customary in railroad practice to employ either a wrought iron or wrought 15 steel yoke strap riveted to the draw bar or a cast yoke having a box or head at the forward end thereof which is keyed to the draw bar. The riveted type of yoke strap is, of course, objectionable for the reason that it 20 is difficult of repair and is a constant source of trouble because of the shearing of the rivets. All cast yokes are objectionable because of the difficulty of casting a yoke which is of perfect material throughout. 25 Furthermore, cast steel in the yoke arms is not as good as a tension member as the wrought iron or wrought steel. The object of my invention, broadly, is to provide a yoke which will eliminate the disadvantages 30 of the two general types of yokes now employed as above mentioned and which will combine the advantages of both.

More specifically, the object of my invention is to provide a detachable yoke for rail- 35 way draft riggings wherein the loop part of the yoke may be formed from wrought iron or wrought steel and the head may be made as a casting, the head being formed in two parts to provide a secure connection between 40 the head and strap.

In the drawing forming a part of this specification, Figure 1 is a part vertical longitudinal section part side elevation of an improved yoke embodying my invention. 45 Figs. 2 and 3 are sectional views taken on the lines 2—2 and 3—3, respectively, of Fig. 1. Figs. 4 and 5 are views corresponding, respectively, with Figs. 1 and 2, but illustrating another embodiment of the invention.

In said drawing, the improved yoke is

shown as comprising what may be termed the strap or loop proper, designated A, and the head, designated generally by the reference B. A draw bar is indicated in dotted 55 lines at C and is of usual form provided with a coupler key slot, as indicated at 10.

The yoke proper A is of general U shape having upper and lower arms 11—11, rear connecting piece 12 and filler block 13. The 60 arms 11 of the strap A, at their forward ends, are offset from the general plane of the arms, as indicated at 14—14, the upper arm being upwardly offset and the lower arm downwardly offset. At their forward extreme ends, the arms are provided with in-turned gibs, as indicated at 15—15. It will also be noted that the offsetting of the arms, as at 14, provides rearwardly facing shoulders, as indicated at 16—16, on the outer 70 sides of the arms and with which the head B is adapted to coöperate, as hereinafter explained.

The head B is formed in two parts, indicated most clearly in Fig. 3 at B' and B''. 75 The outer member B'' is of substantially rectangular form in vertical cross-section and has upper and lower walls 17—17 and side walls 18—18. The latter are forwardly extended, as indicated at 19, in Fig. 1, and 80 provided with transversely arranged slots 20 adapted to aline with the key slot of the draw bar. The inner faces of the side walls 18 are cut away, as indicated at 21—21 in Fig. 3, the contour of the cut-away portions 85 21 being indicated by the full line to which the reference 121 has been applied in Fig. 1. By cutting away the inner faces of the walls 18, as above explained, it is evident that flanges 22 remain which surround the slots 90 20, thereby providing ample wearing area for the coupler key. The upper and lower walls 17 of the part B'' are furnished with transversely extending shoulders 116, which coöperate with the shoulders 16 formed on 95 the yoke strap.

The inner member B' of the head telescopes within and snugly fits the outer member B''. Said inner member B' is formed with upper and lower horizontal walls 100 23—23 and with side walls 24—24, the latter being also forwardly extended and cut

away, as indicated at 25 in Fig. 3, to fit over the inwardly projecting flange-like section 22 of the part B'', in accordance with the contour indicated by the line 121 of 5 Fig. 1.

The parts are assembled as follows: The ends of the arms of the strap A are snapped over the upper and lower walls 23 of the inner head member B' so that the gibs 15 of 10 the strap will engage the front edges of said walls 23, as clearly shown in Fig. 1. Thereafter, the outer head member B'' is slipped longitudinally of the strap A from the rear thereof until it fits snugly over the ends of 15 the yoke strap and is telescoped over the inner head member B'. This condition is illustrated in Fig. 1 and it is obvious that the parts will be held in assembled relation when a coupler key is introduced through the draw 20 bar and the head.

With the arrangement shown, it is evident that the forward ends of the strap are secured snugly between the two elements of the head B and with a connection that is 25 substantially as strong as could be obtained by employing a permanent attachment. At the same time, the connection has the advantage that the head and strap may be readily separated in the case of repair. 30 Furthermore, by providing the shoulders 116 in the outer head member B'', I eliminate a defect that has been present in certain types of yokes heretofore since this shoulder effectively minimizes the tendency of 35 the offset portion 14 of the strap straightening out under tension. It permits me to bring the main portion of the arms 11 of the strap with their inner surfaces flush with the inner faces of the upper and lower 40 walls of the hood and the top and bottom surfaces of the draw bar butt.

Referring to the construction illustrated in Figs. 4 and 5, the yoke strap A' has the forward ends of the arms thereof offset, as 45 indicated at 114, and the extreme ends formed with a T section, as indicated at 30. The head is formed in two detachable parts, indicated at B³ and B⁴. These are telescoped in substantially the same manner as 50 the members B' and B'', except that the inner member B³ is of the same length, horizontally, as the outer member B⁴, as clearly shown in Fig. 5. To accommodate the T ends 30 of the strap A', the inner member 55 B³ is provided with slots 31—31 in the upper and lower walls, as most clearly shown in Fig. 5. The parts are assembled by snapping the T ends 30 of the strap A' in place over the inner member B³, after which the outer member B⁴ is slid longitudinally of 60 the strap until the parts are in the normal position shown in Fig. 4. Without the necessity of going into a further detailed 65 description, it will be evident that the structure shown in Figs. 4 and 5 possesses all

the advantages heretofore set forth in connection with the structure shown in Figs. 1, 2 and 3, particularly with respect to the co-operating shoulders on the strap and outer head member B⁴ to prevent the ends of the 70 strap straightening out under tension.

I claim:

1. A yoke for draft riggings comprising, a strap having a pair of arms and a head detachably united thereto, said arms having 75 offset portions near the ends thereof and the head comprising two rectangular parts between which said offset portions are confined when the parts are assembled, one of said parts fitting within and the other out- 80 side of the ends of the yoke arms.

2. As an article of manufacture, a yoke comprising, a yoke strap having inturned shoulders at the forward ends thereof and a two-part head, the parts of said head being 85 telescoped with respect to each other, one part of said head fitting within the ends of the strap and co-operating with the inturned shoulders thereof, the other part of the head fitting over the ends of the strap. 90

3. As an article of manufacture, a yoke comprising, a strap and a head detachably united thereto, the strap having parallel arms provided with oppositely offset portions at the forward ends thereof and provided with inturned shoulders, said head comprising two parts, one part being disposed within the ends of the arms and engaging the inturned shoulders thereof, the other part encircling the offset portions of 100 said arms and having shouldered engagement therewith to prevent straightening out of the offset portions when the strap is placed under tension. 95

4. As an article of manufacture, a yoke 105 comprising, a strap and a head detachably united thereto, the strap having parallel arms provided with oppositely offset portions at the forward ends thereof and provided with inturned shoulders, said head 110 comprising two parts, one part being disposed within the ends of the arms and engaging the inturned shoulders thereof, the other part encircling the offset portions of said arms and having shouldered engagement therewith to prevent straightening of 115 the offset portions when the strap is placed under tension, the inner surfaces of the arms of the strap being in the same plane as the inner surfaces of the upper and lower walls 120 of the inner part of the head.

5. As an article of manufacture, a yoke comprising, a strap and a head detachably united thereto, the strap having parallel 125 arms provided with oppositely offset portions at the forward ends thereof and provided with inturned shoulders, said head comprising two parts, one part being disposed within the ends of the arms and engaging the inturned shoulders thereof, the 130

other part encircling the offset portions of said arms and having shouldered engagement therewith to prevent straightening of the offset portions when the strap is placed under tension, the head being provided with transversely extending slots adapted to receive a coupler key.

In witness that I claim the foregoing I have hereunto subscribed my name this 14th day of March, 1919.

STACY B. HASELTINE.

Witness:

CARRIE GAILING.
